ELECTRIC VAPORIZER

Joseph Robinson, New York, N. Y., assignor to
 William R. Warner & Co. Inc., New York, N. Y.,
 a corporation of Delaware

Original application July 20, 1935, Serial No.
 32,438. Divided and this application March 4,
 1942, Serial No. 433,380. In the Union of South
 Africa May 16, 1936

6 Claims. (Cl. 128—192)

This application is a division of my application Serial No. 32,438, filed July 20, 1935 (now patent number 2,151,719 granted March 28, 1939), and a division in part of my co-pending application Serial No. 246,528, filed December 19, 1938 which application is itself a division in part of my said application Serial No. 32,438. The subject matter herein disclosed is shown in Figures 8, 15 and 16 of the above application Serial No. 32,438 and in Figures 21 to 23 inclusive of said application Serial No. 246,528.

My invention relates to electric vaporizers of the hand type for generating hot medicated vapors for inhalation in the treatment of head colds, sinus infection, catarrh etc. Among the objects is to provide a "heater, container and applicator unit" supported by a suitable base which is provided with or associated with a switch, the "heater, container and applicator unit" being normally mounted on said base in engagement with the switch and being adapted to be removed therefrom for use. The applicator (sometimes referred to herein as the cover) forming a part of the above unit embraces the container and heater and insulates against the heat therefrom. This permits the user to carry the "heater, container and applicator unit" about in his hand while inhaling the hot medicated vapors, and eliminates the necessity now existing for the user to remain at the electric socket from which current is drawn in generating the vapors. The "heater, container and applicator unit" is so constructed that it may be set vertically upright on a table, desk or the like.

In the accompanying drawing in which like reference characters indicate similar parts,

Figure 1 is a vertical section through my improved vaporizer,

Figure 2 is a bottom view of the heater and container shown in Figure 1, and

Figure 3 is a bottom view of my improvement.

Any suitable materials may be used in constructing my improvement. I preferably make the insulating applicator or cover A of a plastic material having insulating properties, the lower portion of the applicator or cover being relatively thick to increase its insulating capacity. The cover or applicator is provided with a nasal part or nozzle 10 for directing the vapors to the nasal passages. The applicator is perforated at the top as shown, and may be formed integral with the applicator or cover A or separately therefrom. The container C for containing the substance to be vaporized is arranged inside the lower portion of the applicator or cover A and

normally is carried thereby, a split retaining or snap ring 70 is mounted in a circumferential groove in the applicator member and grippingly retains the container therein. The container can, however, be removed from the applicator A as will later be explained. A disc shaped heater H, having a resistance coil arranged in its upper face in a conventional manner, under the mica plate 39, is locked in the skirt portion 108 of the container C by a lock washer 98 which grips the inner walls thereof. This arrangement provides a "heater, container and insulator unit" comprising the heater H, the container C and the applicator cover A with its nozzle or nasal part 10, that is adapted to be removed from the base or stand J for use when the desired vapors are generated. The heat from the heater, while adequate to readily vaporize the medication in the container, does not penetrate the relatively thick lower portion of the applicator cover A, and hence the unit, consisting of the parts above mentioned, namely, the heater H, the container C and the cover or applicator A, may be carried in the hand of the user while inhaling the vapors. Thus the user is not required to remain at the electric socket from which current is drawn. Around the bottom of the container C, and between it and the mica plate 39, I provide a heat absorbing storage member 99 which, in addition to the heater H, retains heat and therefore serves to prolong the presence of heat in the vaporized substance when the "heater, container and applicator unit" is removed from the base J. As stated, the prolongation of heat in the vaporized substance is materially increased by the heat with which the heater itself becomes charged in the process of heating the container C and vaporizing its contents, having in mind that the heater is secured to the container and remains with it when the unit described above is removed from the base.

The base or stand J may be of any conformation suitable for use with the "heater, container and applicator unit." That is to say it may be an elongated hollow handle or it may be formed as shown wherein a neck 92 extends upwardly from the hollow base 93. Lugs 94 are provided on the inner walls of the base J and neck 92, and to these the switch blades 42—43, and the electric cord K, are firmly secured by suitable screws 47. Ribs 95 extend upwardly along either side of the switch blades and fit snugly against them to prevent the blades tilting on their supports 94. Both blades are preferably made of resilient material, such as spring brass, and each

is turned inwardly at its upper end 96-97 to facilitate circuit communication between the heater H and the cord K. This is accomplished by pressing the "heater, container and applicator unit" down until the lock washer 98 engages the top 102 of the base J. This brings the contact washer 103 of the heater H into engagement with the top 96 of the switch blade 42, and since the centrally arranged screw or contact member 106 of the heater normally rests on the top 97 of the switch blade 43, and co-operates with the blade to support the "heater, container and applicator unit" vertically on the base J, an electric circuit through the heater is formed when the contact washer 103 meets the blade 42. By holding the "heater, container and applicator unit," consisting of parts A, C and H, at the bottom of its downward movement a few seconds the medicament to be vaporized is heated to the desired temperature, and substantial heat is stored in the heater H and storage member 99 and entrapped in the chamber 104. The "heater, container and applicator unit" may then be lifted off the base J and carried in the hand of the user while he walks about his home or office and inhales the hot, soothing vapors. During this inhalation currents of air are lifted up through the volutes 105 of the cover A into the container C, and are heated as they travel upwardly against the hot sides of the container. Removal of the downward pressure on the "heater, container and applicator unit" permits the switch blade 43 to return the unit to the normal position shown in Figure 1 thereby breaking the electric circuit, and extinguishing the heater.

While, as aforesaid, the snap ring 70 grips the container with sufficient pressure to cause the container and the heater to travel with the applicator cover A, and to hold said cover, heater and container assembled as a unit, the pressure is not such as to prevent removal of the applicator cover A from the container C for the purpose of inserting the substance to be vaporized or emptying the container after vaporization of the substance. To facilitate this removal the container is provided at its bottom with a slight flange 100 and the insulating applicator cover A is provided with a plurality of openings 101. Removal is done by inserting the thumb and forefinger in two of the openings 101 and pulling down on the flange 100 or up on the cover A.

While any suitable form of heater H may be used with my improvement, perhaps it should be noted that both ends of the heretofore mentioned resistance coil, one end of which is shown at 26 in Figure 2, are anchored under the centrally located screw 106, and that the lock ring 108 is provided with lugs 107 which fit in complementary openings in the bottom of the heater to prevent undesired rotation of the heater in the sleeve or skirt 108 of the container C. Inasmuch as the heater engages the bottom of the container C and is held in that position by the lock ring 98, it is proper to say that this ring acts also to retain the resistance coil of the heater, and the mica disc 39, in place. Proper positioning of the assembled unit comprising the heater H, the container C and the insulating

applicator cover A, flows from the slip fit of this unit over the upper end of the base J. Lateral shifting of the unit and tilting thereof on the base is in this manner prevented, whilst extending the bottom of the cover A past the lowest part of the heater and container protects the user against contact with these parts when they are hot.

What I claim is:

- 10 1. An electric vaporizer comprising in combination, a base, a switch terminal and electric cord assembly in said base, and a heater-container applicator unit seated on said base with the heater in circuit with said assembly, said unit comprising a container for the substance to be vaporized, a heater in contacting relation to said container and portable therewith for heating said container and said substance and for prolonging the retention of heat therein, an applicator surrounding and insulating said container and heater and including a nozzle for directing the vapors, and connecting means for connecting the heater, container and applicator parts of the unit to enable removal of said unit as such from said 15 base and cord assembly for transport and use away from and independent of said base and cord assembly.
- 20 2. A vaporizer device comprising a base, a switch in said base including a pair of terminals, a heater having a terminal which yieldably contacts one of said switch terminals to normally hold the heater in elevated position, a container for the substance to be vaporized, said container being adapted to be heated by said heater and being depressible to bring the heater into contact with the other switch terminal to effect closing of the electric circuit, and a cover for insulating said container and for directing the vapors.
- 25 3. A vaporizer according to claim 2 wherein the 30 first mentioned switch terminal operates to break the electric circuit when pressure upon the heater is removed.
- 35 4. An electric vaporizer as set forth in claim 1, in which the base is provided with a switch 30 blade and in which said applicator slips over the upper end of said base and extends below said heater to surround the upper part of said base and position the heater-container-applicator unit thereon with a part of said heater engaging 45 said switch blade, said heater being provided with a vertically arranged contact member adapted to engage with said switch blade, said applicator serving also to insulate said container and said heater so as to enable handling of the heater-container-applicator unit when heated by the applicator after removal from the base.
- 50 5. A vaporizer as set forth in claim 1, wherein the connecting means is disposed in approximately a horizontal plane and engages the inner 55 wall of the applicator to assure removal of the heater with the applicator and thus provide the removable unit.
- 60 6. A vaporizer as set forth in claim 1, wherein the applicator is provided with vertical grooves forming air spaces to increase the effectiveness of the insulation afforded by said applicator.

JOSEPH ROBINSON.
